UNITED STATES PATENT OFFICE.

ROBERT N. CORTHELL, OF AUBURN, MAINE, ASSIGNOR TO SUMMIT THREAD COMPANY, OF EAST HAMPTON, CONNECTICUT, A CORPORATION OF MAINE.

BOBBIN-CONTROLLING ADJUNCT FOR SEWING-MACHINE SHUTTLES.

Application filed April 27, 1927. Serial No. 186,860.

This invention relates to a bobbin composed of an annular thread mass universally wound on a paper cop tube. A bobbin of this description is commonly used in a shuttle known as the Singer D 12, which includes a bobbin case composed of a head and an annular wall, the wall having a threading slot whose mouth is at the open end of the wall, the slot extending partly to the head. The shuttle has a center post extending from a post-supporting member on the shuttle body through a hollow post on the case head, the bobbin being rotatable about said posts within the bobbin case.

It is important that the bobbin be maintained in such position that thread passing therefrom will always be within the threading slot at a distance from the mouth thereof and cannot slide out of the mouth and become fouled with parts of the shuttle, the proper course of the thread from the bobbin to the stitch-forming mechanism being through the inner or closed end of the threading slot and between the external surface of the wall and the usual tension device on said external surface. If the bobbin is of less than the predetermined length intended for this type of shuttle, the above-mentioned liability of fouling the thread exists in a marked degree and is often the cause of annoyance and loss of time.

My invention has for its object to obviate the above-mentioned liability and ensure the proper passage of the thread from the bobbin to the stitch-forming mechanism through the threading slot. This object is attained by the employment of an adjunct engageable by friction with the tube of a ready wound bobbin so that it is adapted to rotate therewith and be transferred from the tube of a spent bobbin to the tube of a full one, the adjunct including a spring adapted to bear on a supporting portion of a shuttle adjacent the bobbin case and press one end of the bobbin against the head of said case, thus ensuring the maintenance of the opposite end in position to prevent the thread passing therefrom from sliding out of the mouth of the threading slot.

Of the accompanying drawings,

Figure 1 is a plan view of a shuttle to which a bobbin having my improved adjunct is applicable.

Figure 2 is a section on line 2—2 of Fig-

ure 1, the bobbin case being shown in elevation.

Figure 3 shows in section on line 3—3 of Figure 2 and on a larger scale, the bobbin case, and a bobbin therein having my improved adjunct.

Figure 4 is a face view of the adjunct looking toward the outer face thereof.

Figure 5 is a section on line 5—5 of Figure 4.

Figure 6 is a sectional perspective view showing the adjunct alone.

Figure 7 is a sectional perspective view showing the bobbin and the adjunct applied thereto.

The same reference characters indicate the same parts in all the figures.

A bobbin to which my invention relates shown by Figures 3, 6 and 7, includes a paper cop tube 12 and an annular thread mass 13 wound thereon usually by the method 75 known as universal winding.

My improved adjunct is composed of an annular sheet metal head 14 formed to bear on and cover the inner end of the bobbin, this being the end farthest from the head of the bobbin case, and a spring of thin resilient sheet metal, a portion of which is fixed to the outer surface of the head 14 at one side of the center thereof. The head 14 is provided at its center with a short integral 85 tube or tubular shank 16 formed to have a close frictional fit in the bore of the cop tube 12. The spring includes an ear 17 (Figure 4) which is soldered, brazed, electrically welded, or otherwise rigidly secured to the outer face of the head 14 near the margin thereof and at one side of the tubular shank 16, and a free annular shoe 18 integral with the ear and maintained thereby yieldingly spaced from the outer side of the head as 90 shown by Figures 5, 6 and 7. The central opening 19 of the annular shoe coincides with the bore of the tubular shank 16 and is formed to receive the hub portion 20^a (Figure 3) of the usual center post 20 on 95 which the bobbin case of a shuttle of the type illustrated, is mounted. The bobbin case in this type of shuttle is composed of a head 21 and an annular curb or wall 22 having an inclined threading slot 23 extending 100 from the open end of the wall partly to the head, and terminating in an enlargement 105 covered by the usual tension device 24. The

head usually has a tubular center post 25 (Figure 3) which receives the center post 20 of the shuttle. The post 20 is supported by a member 35 of the shuttle body.

5 When the shuttle is in operation the bobbin rotates about the posts 20 and 25, the tubular shank 16 being frictionally engaged with the bore of the cop tube so that the adjunct is, in effect, a part of the bobbin, the adjunct and bobbin rotating as a unit as the thread is drawn off. The shoe 18 bears on the shuttle member 35 as shown by Figure 3, and maintains the outer end of the bobbin against the head 21 of the bobbin case, and the inner end of the bobbin offset inwardly from the open end of the bobbin case wall and from the open end or mouth of the threading slot 23, so that the thread unwinding from any portion of the bobbin 10 is offset from the mouth of the threading slot and is not liable to slide out of said mouth and become fouled or entangled with any part of the shuttle.

15 The tubular shank 16 when frictionally engaged with the tube 12 of an operative bobbin, secures the head 14 and the shoe 18 to the bobbin as indicated by Figure 7, the bobbin and the adjunct being adapted to be installed as a unit in the shuttle. When 20 the bobbin is spent, the adjunct may be withdrawn from the cop tube and inserted in the tube of an operative bobbin.

25 My improved adjunct is not limited to use in a shuttle of the particular type here shown. Figure 3 shows a sheet metal head

27 covering the outer end of the bobbin and engaged with the cop tube thereof by a tubular shank 28. This head is well known and is not claimed by me.

30 I claim:

For use with a sewing machine shuttle of the character referred to, having a head at one end and a threading slot formed in its annular wall and open at one end, and a bobbin, comprising a cop tube and an annular thread mass wound thereon and having slightly convex end surfaces, said case being adapted to move bodily relative to the shuttle in the direction of the length of the cop tube when the shuttle is operating, a bobbin 45 controlling adjunct composed of a concaved annular head formed to bear on the inner end of the bobbin and provided with a tubular shank formed to enter and frictionally engage the cop tube, and a resilient sheet 50 metal spring comprising a free annular shoe yieldingly connected to the head and maintained spaced therefrom by an ear, the orifice of said shoe coinciding with the tubular shank of the head to receive the hub of the 55 shuttle post about which the bobbin, head and spring are rotatable as a unit, the spring being adapted to bear on a member of the shuttle to maintain the bobbin within the bobbin case beyond the open end or mouth of 60 the threading slot in the bobbin case.

65 In testimony whereof I have affixed my signature.

ROBERT N. CORTHELL.
